DOOR OPERATING MECHANISM

Victor O. Keys, Lexington, Ky.

Application September 15, 1934, Serial No. 744,211

5 Claims. (Cl. 268—62)

This invention relates to a door operating mechanism, and it is primarily an object of the invention to provide a mechanism of this kind for use in connection with garage doors and whereby such doors may be readily and conveniently opened or closed by an occupant of the vehicle.

Another object of the invention is to provide a mechanism of this kind whereby the doors when closed are effectively held in such position.

10 The invention also has for an object to provide a mechanism of this kind wherein the operation thereof is under control of a swinging lever extending a desired distance exteriorly of the building structure.

15 The invention consists in the details of construction and in the combination and arrangement of the several parts of my improved door operating mechanism whereby certain important advantages are attained and the device rendered 20 simpler, less expensive and otherwise more convenient and advantageous for use, as will be hereinafter more fully set forth.

The novel features of my invention will hereinafter be definitely claimed.

25 In order that my invention may be the better understood, I will now proceed to describe the same with reference to the accompanying drawings, wherein:—

Figure 1 is a view partly in top plan and partly 30 in section illustrating a door operating mechanism constructed in accordance with an embodiment of my invention, the line of section being substantially on the line 1—1 of Figure 2, with portions omitted;

35 Figure 2 is a vertical sectional view taken substantially on the line 2—2 of Figure 1;

Figure 3 is a fragmentary detailed sectional view taken substantially on the line 3—3 of Figure 2, looking in the direction of the arrow:

40 Figure 4 is an enlarged fragmentary sectional view taken substantially on the line 4—4 of Figure 1;

Figure 5 is a sectional view taken substantially on the line 5—5 of Figure 1.

45 In the accompanying drawings, B denotes a building structure of a type particularly designed for use as a garage and which includes a pair of outwardly swinging doors D associated with the entrance to the structure. These doors are hung in a manner to swing inwardly one toward the other as is clearly illustrated in the accompanying drawings.

The wall of the structure B provided with the entrance opening has supported above such entrance opening a sill member 1, said member be-

ing provided centrally of said opening and having secured thereto the forward end portions of the parallel tracks 2 extending inwardly of the structure B a required distance. The tracks 2 provide a support for a sliding head 3 which has movement toward or from the entrance and the forward marginal portion of said slide 3 is provided in a direction thereacross with the spaced openings 4.

These openings 4 permit an adjustable pivotal connection to the slide 3 with respect to its transverse center of the inner end portions of the elongated rigid members or rods 5. The outer end portions of these rods 5 are pivotally connected, as at 6, to the doors D. By this means as the slide 3 is moved outwardly along the guides or trackways 2 the doors D will be thrown into open position and vice versa. While of course the extent of opening movement of the doors D will be mainly dependent upon the extent of movement 50 of the slide 3, it is believed to be apparent that such opening movement can be further regulated or controlled by adjusting the pivotal connection of the members or rods 5 with the slide 3 as permitted by the openings 4 hereinbefore referred to.

The rear portion of the slide 3 at its transverse center carries a bracket 7 with which is pivotally connected a pitman or push rod 8. This pitman or rod 8 in turn is operatively connected with a crank 9 comprised in the shaft 10. This shaft 10 is rotatably supported within the building structure B at a preferred location and the throw of the crank 9 will determine the maximum extent of opening the doors D.

The guides or trackways 2 as herein disclosed 35 are further maintained in desired effective position by a suitably supported beam 11, said guides or trackways being secured thereto from below.

The shaft 10 is provided as herein disclosed 40 with a second crank 12 preferably positioned to one side of the entrance and operatively engaged with the crank 12 is a link 14 which is also pivotally connected, as at 15, with the inner end portion of an elongated operating member or lever L. This lever L extends exteriorly of the building structure B through a suitably positioned opening 14 and at a desired point intermediate its ends the lever L is supported, as at 15, for rocking movement in a vertical direction. The outer or exterior end portion of the lever L has operatively engaged therewith a pull rod 16 which may be readily grasped by an occupant 45 of the vehicle to operate the lever L to throw open or closed the doors D. Upon pull on the member 16 the inner end portion of the lever L 50

will swing upwardly resulting in an outward movement of the slide 3 with the desired opening of the doors D. While of course upward push upon the rod or member 16 will result in a closing of 5 the doors.

The inserted end portions of the lever L is continued by an upwardly and rearwardly disposed arm 17 provided at its free extremity with an undercut recess or notch 18. The arm 17 is of such 10 formation and the notch or recess 18 is so positioned that as the inner end portion of the lever L is swung downwardly to close the doors, the notch or recess 18 will engage over an outstanding lug or flange 19 carried by the shaft 15 10 just as the doors D are fully closed. This engagement serves to effectively hold the doors when closed against accidental opening.

From the foregoing description it is thought to be obvious that a door operating mechanism 20 constructed in accordance with my invention is particularly well adapted for use by reason of the convenience and facility with which it may be assembled and operated, and it will also be obvious that my invention is susceptible of some 25 change and modification without departing from the principles and spirit thereof and for this reason I do not wish to be understood as limiting myself to the precise arrangement and formation of the several parts herein shown in carrying out my invention in practice except as herein-after claimed.

I claim:—

1. An operating mechanism for a door comprising a slide, means for supporting the slide for movement in substantially a fixed path of travel, door engaging means connected to the slide, a shaft having a plurality of cranks, a pitman interposed between and connected to the slide and one of the cranks, a lever, means engaged 35 with the lever intermediate its length for supporting the lever for rocking movement, an operative connection between one end portion of the lever and the second crank of the shaft, and coacting means carried by the lever and the shaft 40 for holding the shaft against rotation when the slide is at the limit of its closing movement.

2. An operating mechanism for a door comprising a slide, means for supporting the slide for movement in substantially a fixed path of travel, door engaging means connected to the slide, a shaft having a plurality of cranks, a pitman interposed between and connected to the slide and one of the cranks, a lever, means engaged 45

with the lever intermediate its length for supporting the lever for rocking movement, an operative connection between one end portion of the lever and the second crank of the shaft, a lug carried by the shaft, an arm carried by the lever having a recess to receive the lug of the shaft when the lever has been moved in a direction to impose closing movement to the slide. 5

3. An operating mechanism for a door comprising a slide, means for supporting the slide 10 for movement in substantially a fixed path of travel, door engaging means connected to the slide, a shaft having a plurality of cranks, a pitman interposed between and connected to the slide and one of the cranks, a lever, means engaged 15 with the lever intermediate its length for supporting the lever for rocking movement, an operative connection between one end portion of the lever and the second crank of the shaft, a lug carried by the shaft, an arm carried by the lever having a recess to receive the lug of the shaft when the lever has been moved in a direction to impose closing movement to the slide, said arm being angularly disposed with respect to the adjacent end portion of the lever. 20 25

4. An operating mechanism for a door comprising a slide, means for supporting the slide for movement in substantially a fixed path of travel, door engaging means connected to the slide, a shaft, a pitman operatively connected to 30 the slide and to the shaft for imparting endwise movement to the slide upon rotation of the shaft, a rock lever, an operative connection between the lever and the shaft for rotating the shaft upon rocking the lever, and coacting means carried by the lever and the shaft for holding the shaft against rotation when the slide is at the limit of its closing movement. 35

5. An operating mechanism for a door comprising a slide, means for supporting the slide 40 for movement in substantially a fixed path of travel, door engaging means connected to the slide, a shaft, a pitman operatively connected to the slide and to the shaft for imparting endwise movement to the slide upon rotation of the shaft, a rock lever, an operative connection between the lever and the shaft for rotating the shaft upon rocking the lever, a lug carried by 45 the shaft, and an arm carried by the lever having a recess to receive the lug of the shaft after the lever has been rocked. 50

VICTOR O. KEYS.
